UNITED STATES PATENT OFFICE.

FRANK F. KRAUSE, OF CASHMERE, WASHINGTON.

WATER PUMP AND AERATOR FOR COOLING SYSTEMS.

1,370,823.

Specification of Letters Patent.

Patented Mar. 8, 1921.

Application filed May 26, 1920. Serial No. 384,421.

To all whom it may concern:

Be it known that I, FRANK F. KRAUSE, a citizen of the United States, residing at Cashmere, in the county of Chelan and State of Washington, have invented certain new and useful Improvements in Water Pumps and Aerators for Cooling Systems, of which the following is a specification.

This invention relates to water pumps and aerators for cooling systems, and is an improvement on my allowed application Serial No. 310,689, filed July 14, 1919, and the primary object of the present invention is to provide means for positively circulating the cooling fluid through the cooling system and for positively aerating the same prior to its entrance to the cooling jackets of the device or motor to be cooled, thereby insuring that the cooling fluid will be acted upon by the incoming air and be effectively cooled, so that a maximum benefit will be obtained from the cooling fluid.

Another object of the invention is to provide a means for forcing a steady stream of the cooling fluid against the aerating blades, and for checking the rotary movement of the cooling fluid as the same is being acted on by the aerating blades.

A further object of the invention is to provide an improved means for automatically closing the air intake pipe for the aerating blades when the motor is not in operation, so as to prevent the escape of the cooling fluid from the air intake pipe.

A further object of the invention is to provide an improved air intaking blade for the cooling fluid, which is so constructed as to permit a maximum amount of air to be taken in from the intake pipe through the blade and for mixing the same with the cooling fluid.

A further object of the invention is to provide an improved water pump for cooling systems of the above characters, which is durable and efficient in use, one that is simple and easy to manufacture, one that can be placed upon the market at a reasonable cost, and one which can be installed cheaply and conveniently in existing cooling systems or embodied therein at the time of manufacture.

A still further object of the invention is to provide an improved means for rotatably mounting the hollow shaft carrying the circulating propeller and the aerating blades,

so as to effectively hold the shaft in alignment and to eliminate all end thrust.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a side elevation of the improved pump and aerator showing the same applied to the power plant of a motor vehicle.

Fig. 2 is a longitudinal section through the improved pump and aerator.

Fig. 3 is a fragmentary longitudinal section through the pump and aerator, taken at right angles to Fig. 2.

Fig. 4 is a transverse section taken on the line 4-4 of Fig. 2, showing the construction of the circulating propeller.

Fig. 5 is a transverse section taken on the line 5-5 of Fig. 2 showing the construction of one of the aerating blades.

Referring to the drawings in detail, wherein similar reference characters designate corresponding parts throughout the several views, the letter A indicates the improved pump and aerator, and B the cooling system for an internal combustion engine C, which the same is associated with.

It is to be understood, however, that the improved pump and aerating device may be used with any cooling system with any type of machine or motor either of the portable or stationary type. The cooling system B includes the radiator D which is of the usual or any preferred construction and the inlet and outlet pipes E and F. The inlet pipe E communicates with the water jacket of the internal combustion engine C in the ordinary manner, while the lower outlet pipe F of the radiator has interposed therein the improved pump and aerating device A.

The improved pump and aerating device A includes a horizontally disposed cylinder 10, the forward end of which is provided with the removable cap 11 which is provided for the purpose of facilitating the positioning of the operating shaft 12 in the cylinder. The end of the cylinder opposite to the end which carries the cap 11 is provided with a sleeve 13 which is adapted to receive the brass bushing 14, for the inner end of the shaft 12. This end of the shaft is provided

with a collar 15 which is formed integrally therewith and secured thereto in any preferred manner and this collar bears against the inner end of the brass bushing 14. The 5 end cap 11 is also provided with a bearing 16 which receives the opposite end of the shaft and this end of the shaft is provided with a collar 17, which is rigidly secured to the shaft and the same is adapted to engage 10 the inner end of the bearing 16. The provision of the collars 15 and 17 absolutely precludes all endwise movement of the shaft and it can be seen that the bushing 14 can be so positioned as to force the collar 17 15 into the engagement with the bearing 16. The outer end of the sleeve 16 protrudes beyond the cap 11 and the same is provided with a stuffing box 18 so as to prevent the leakage of water around the shaft 12 and out of 20 the cylinder. Hard oil cups 14' are provided, so as to permit the correct lubrication of the bearings. The opposite end of the cylinder has its bearings 13 internally screw threaded as at 19 for the reception of the air inlet 25 pipe 20, the outer end of which is provided with the automatic control valve 21. The shaft 12 is of hollow formation and has its bore communicating with the bore of the intake pipe 20, so that the air from said 30 pipe may be taken into the shaft. The extreme forward end of the shaft 12 has keyed or otherwise secured thereto a drive pulley 22, which may be driven in any preferred manner from the power plant D. 35 A belt 23 is shown for driving the pulley 22 and this belt may also be connected to the fan pulley for driving the fan. If so desired, the shaft 12 may be formed in two sections, a hollow section 24 and the solid 40 section 25. When the shaft is made in this manner the forward end of the hollow section is provided with a socket for receiving the inner end of the solid structure. The forward end of the cylinder 10 has communicating with its lower end the outlet pipe F of the radiator B or if so desired the cylinder itself may be provided with an integral depending pipe section 27 which 45 may be connected through the medium of a flexible hose 28 with the outlet pipe F of the radiator. The opposite upper end of the cylinder 10 is provided with a forwardly and upwardly inclined pipe 29 which is connected to the inlet end of the water jacket 50 of the power plant in the usual or any preferred manner.

Directly in front of the depending pipe 55 the shaft has secured thereto a circulating propeller 30 which is adapted to force cooling fluid in a solid stream against the aerating blades 31, which will be hereinafter more fully described. The circulating propeller 30 as shown includes a hub 32 which is keyed or otherwise secured to the shaft 60 and the outwardly radially extending dia-

metrically disposed propeller blades 33. The propeller blades 33 are of solid formation as can be clearly seen from the drawings.

The aerating blades 31 are arranged at 70 quarters on the shaft and as shown the same are four in number, but it is to be understood that more or less can be used if so desired. In fact good results may be obtained by the use of a single aerating 75 blade. The aerating blades 31 are of hollow formation and communicate with ports 34 formed in the hollow portion of the shaft 12 and the air is adapted to be sucked through the intake pipe 20, the hollow portion of the shaft 12, through the ports 34, and through the hollow blades into the water or other cooling fluid in the cylinder. Each of the aerating blades includes a hollow shank 35 and the inclined side wings 36 80 85 which are connected at one of their edges which forms a substantially V-shaped arrangement in cross section. The converging sides of the wings or plates forms a sharp end for cutting through the water. As the shaft is rotated the converged portion of the blade will cut through the water and create a suction in rear thereof for sucking the air into the water through the hollow portion of the shaft 12.

95

The automatic cut off 21 includes a casing 37 which is formed by enlarging the upper end of the pipe 20 and the upper end of the casing is provided with a removable top wall 38, which supports the removable air intake nozzle 39. The lower end of the air intake nozzle 39 is provided with a valve seat 40 on which is adapted to fit the semi-spherical valve 41. The valve 41 is of hollow formation so as to effectively reduce the 100 weight thereof and this valve is guided in its movement by depending guide fingers 42, which are carried by the nut 43 which is provided for holding the air intake nozzle 39 in place. The valve 41 carries a depending valve stem 44 which is in turn connected to a spider 45, which is carried by the float 46, which may be formed of cork or any preferred material. The float 46 is provided with an axial bore so as to permit the flow of 105 air through the same. The air intake nozzle 39 is also provided with a manually operated valve 47 which is provided with an operating rod 48, which may extend to the dash board of a motor vehicle, so as to permit the driver 110 of the vehicle to readily open and close the same.

115

The cylinder 10 is provided at spaced points with a plurality of inwardly extending fins or stationary baffle blades 49, between which the aerating blades 31 are adapted to ride. The inner edges of the baffle blades 49 are inclined as at 50 so as to conform to the configuration of the aerating blades and these stationary baffle blades 49 120 125 130

are provided so as to prevent the radial movement of the cooling fluid in the cylinder and thereby permit the blades to act on the same with a maximum amount of efficiency.

In operation of the improved pump and cooling fluid aerator, when the power plant is in operation, the shaft 12 in the cylinder will be rotated therewith, which will cause the circulating propeller to force the water through the cylinder in a solid sheet against the aerating blades 31. The blades 31 cut through the water and create a suction at the following portions thereof and suck in the air through the intake nozzle 39, valve 21, the pipe 20 and the shaft 12. The baffle blades 49 form an effective means, as stated, for preventing a whirling motion of the water through the cylinder. Thus it can be seen that an effective means is provided for circulating and aerating the water for cooling systems. When the motor is stopped the cooling fluid will enter the shaft 12 through the aerating blades 31 and flow into the pipe 21 and the valve casing 37, which will raise the float 46 and force the valve 41 on its seat, which will effectively prevent the escape of the cooling fluid from the air intake nozzle. The manual operated valve 47 is provided for preventing the inlet of the air to the shaft when necessary or desirable.

Changes in details may be made without departing from the spirit or scope of the invention; but,

I claim:

1. The combination with a cooling system, of a propeller mounted in the cooling fluid thereof, and means for conducting air into the fluid in advance of the propeller.
2. The combination with a cooling system, of air intake members arranged in the cooling fluid of the system, and means for forcing the cooling fluid against said members.
3. The combination with a cooling system, of an internal combustion engine, of rotatable air intake members arranged in the cooling fluid thereof, and means for directing the cooling fluid against the rotary air intake members.
4. The combination with a cooling system, of an internal combustion engine, of a pump therefor, and means arranged in advance of the pump for introducing air into the cooling fluid.
5. The combination with a cooling system, of an internal combustion engine, of a circulating pump therefor, and rotary air intake members arranged in the cooling fluid at one side of the pump circulating member.
6. The combination with a cooling system of an internal combustion engine, of a circulating pump therefor, rotatable air intake members arranged in the cooling fluid, and means for simultaneously operat-

ing the circulating pump and the rotatable air intaking members.

7. The combination with the cooling system of an internal combustion engine, of a circulating pump arranged in the system, rotatable air intaking members arranged in the cooling fluid of the system, and automatic means for shutting off the atmospheric connection of the air intaking members upon the stopping of the circulating pump.

8. The combination with the cooling system of an internal combustion engine, of a circulating pump therefor, rotatable air intaking members mounted in the cooling fluid of the system, means for rotating said rotatable air intaking members, and automatic means for shutting off the atmospheric connection of the air intaking members when the same are not in motion.

9. The combination with a cooling system of an internal combustion engine, of a rotatable propeller arranged in the cooling fluid thereof, rotatable air intaking members arranged in the cooling fluid, means for rotating the propeller and air intaking members, and means for cutting off the supply of air to the air intaking member.

10. The combination with the cooling system of an internal combustion engine including a radiator and an outlet pipe, of a circulating and aerating attachment for the cooling fluid therefor including a cylinder, means connecting one end of the cylinder with the outlet pipe of the radiator, means operatively connecting the opposite end of the cylinder with the cooling jacket of the internal combustion engine, a propeller arranged in the cylinder, and air intaking members arranged in the cylinder in advance of the propeller.

11. The combination with the cooling system of an internal combustion engine including a radiator and an outlet pipe, of a circulating and aerating attachment for the cooling fluid including a cylinder, means connecting one end of the cylinder with the outlet pipe of the radiator, means connecting the opposite end of the cylinder with the water jacket of the internal combustion engine, a hollow shaft rotatably mounted in the cylinder, means for rotating the shaft from the internal combustion engine, a propeller carried by the shaft for rotation therewith arranged in the cylinder in advance of the outlet pipe of the radiator, and air intaking blades carried by the shaft and communicating with the bore thereof.

12. The combination with the cooling system of an internal combustion engine including a radiator and an outlet pipe, of a circulating and aerating device for the cooling fluid thereof including a horizontally disposed cylinder, means operatively connecting one end of the cylinder with the outlet

- pipe of the radiator, means connecting the opposite end with the water jacket of the internal combustion engine, a hollow shaft arranged longitudinally in the cylinder and 5 rotatably carried by the terminals thereof, means connecting the hollow shaft with the atmosphere, a propeller carried by the shaft for rotation therewith, a plurality of radially arranged air intaking blades carried 10 by the hollow shaft communicating with the bore thereof, means for rotating the shaft, and automatic means arranged in the means for connecting the hollow shaft with the atmosphere for cutting off the connection 15 with the hollow shaft when the cooling fluid flows into said shaft.
13. The combination with the cooling system of an internal combustion engine including a radiator, a water jacket for the 20 internal combustion engine, inlet and outlet pipes connecting the radiator with the water jacket, of a device for circulating and aerating the cooling fluid comprising a cylinder, means connecting one end of the cylinder 25 with the outlet pipe of the radiator, means connecting the opposite end of a cylinder with the water jacket of the internal combustion engine, a hollow shaft rotatably mounted in the cylinder, means for rotating the 30 shaft, a propeller carried by the shaft for rotation therewith arranged in the cylinder in advance of the connection of the outlet pipe of the radiator therewith, a plurality of radially extending air intaking blades 35 carried by the shaft and communicating with the bore thereof, an air intake pipe communicating with the hollow shaft, an automatic valve arranged in the pipe adapted to close when the cooling fluid flows within said 40 intake pipe, and a manually operated valve arranged in said air intake pipe.
14. In a circulating and aerating device 45 for cooling systems, an air intaking blade including a hollow stem, and outwardly extending converging wings carried by the hollow stem.
15. In a circulating and aerating device for cooling systems, an air intaking blade including a hollow stem, outwardly extending wings carried by the stem, the wings being arranged in converging relation to each other to provide a cutting edge.
16. The combination with a cooling system for internal combustion engines, comprising a radiator, a water jacket for the 55 internal combustion engine, outlet and inlet pipes for the radiator, of a circulating and aerating device for the cooling fluid of the system comprising a horizontally disposed cylinder, bearings carried by the opposite 60 ends of the cylinder, a hollow shaft rotatably mounted in said bearings, means for rotating the hollow shaft, an air intake communicating with one end of the hollow shaft, a valve casing formed on the upper end of 65 the intake pipe, a float arranged in said valve casing, an air intake nozzle carried by the valve casing, a hollow semi-spherical valve carried by said float and arranged to fit on said seat, a propeller secured to said 70 shaft, an air intake blade carried by the shaft and communicating with the bore thereof, said blade including a hollow stem, outwardly extending converging wings, and means connecting the cylinder with the outlet 75 pipe of the radiator and with the water jacket of the internal combustion engine.
17. As a new article of manufacture, a cylinder, operatively extending inlet and outlet pipes formed on the opposite ends of 80 the cylinder, a rotatable shaft arranged longitudinally in the cylinder, said shaft having an axial bore, a propeller carried by the shaft for rotation therewith, a plurality of outwardly extending air intake blades arranged intermediate the inlet and outlet 85 pipes, an air intake pipe carried by the cylinder and communicating with the bore of the shaft, and an automatic manually operated valve arranged in said air intake pipe.

FRANK F. KRAUSE.
